UNITED STATES PATENT OFFICE

ROBERT S. BLAIR, OF STAMFORD, CONNECTICUT, ASSIGNOR TO EVANS CASE COMPANY, OF NORTH ATTLEBORO, MASSACHUSETTS, A CORPORATION OF MASSACHUSETTS

LIGHTER CONSTRUCTION

Application filed December 13, 1928. Serial No. 325,746.

This invention relates to lighting devices and more particularly to those in which a wick is ignited by sparks from pyrophoric metal or other suitable sparking material.

5 One of the objects thereof is to provide a practical device of the above type of simple and durable construction and which is efficient and dependable in action. Further objects are to facilitate the actuation of the 10 spark producing mechanism, to eliminate gearing, to prevent discoloration of the snuffer, to provide convenient access to the burner when the snuffer is raised, to reduce the number of parts, and in general to provide 15 an improved lighter of this type. Other objects will be in part obvious and in part pointed out hereinafter.

The invention accordingly consists in the features of construction, combinations of elements, and arrangements of parts which will be exemplified in the apparatus hereinafter described and the scope of application of which will be indicated in the following claims.

25 In the accompanying drawing, in which is shown one of the various possible embodiments of this invention:—

Fig. 1 is a side elevation with portions broken away to expose the parts concealed thereby;

Fig. 2 is an enlarged detail view of portions of the device;

Fig. 3 is an enlarged plan view and

Fig. 4 is a vertical sectional view on the 35 line 4—4 of Fig. 2.

Similar reference characters refer to similar views throughout the several figures of the drawing.

Referring now to the drawing in detail, 40 there is shown a fuel tank 5 provided with the customary filling of absorbent material and openings through which liquid fuel may be poured when the tank is inverted. A burner 6 is provided on the elongated top 45 wall 7 of the tank and this contains an absorbent wick 8 which extends into the tank in the usual manner.

Formed upon the upper surface of the top wall 7 are a pair of webs 9 and 10. Journaled in these webs is a shaft 11 on which is

loosely mounted a suitable abrasive wheel 12 and a pressed metal actuating member 13. Pressing against the lower surface of the wheel 12 is a short cylindrical piece of pyrophoric metal 14 resting within a tube 15 extending downwardly into the fuel tank and this pyrophoric metal is urged toward the wheel by means of a long spiral spring (not shown) within the tube 15 as is customary in such devices. A ratchet 16 is likewise loosely mounted upon the shaft 11 and fixed to the wheel 12.

A second shaft 17 is journaled in the webs 9 and 10 in the same manner as the shaft 11 and on this shaft is loosely mounted a 65 pressed metal arm 18 carrying on its free outer end a snuffer 19. This snuffer is in the form of a cap which in closed position fits closely over the reduced upper end 20 of the burner and its edge presses tightly 70 against the beveled shoulder 21 thereon to seal in the exposed wick end and prevent evaporation or waste of fuel therefrom. A ratchet arm 22 is pivotally mounted on a cross pin 23 set in the snuffer arm 18 and 75 this ratchet arm is yieldingly held in contact with the ratchet 16 by means of a suitable spring as 24.

The actuating member 13 consists of a broad finger piece 25 from the opposite side 80 walls of which extend a pair of arms 26, one being disposed on each side of the snuffer arm 18. The forward extremity of each of these arms 26 is pivotally mounted on the shaft 11. Each of these arms 26 is preferably 85 cut away as at 27 to admit the shaft 17 when the actuating member is in its depressed position, as indicated in Fig. 2. A tubular shaft or sleeve 28 extends between the arms 26 of the actuating member and this shaft is 90 supported by a pin 29 which extends through the arms and fits within the bore of the shaft so that the shaft is revoluble thereon.

The snuffer arm 18 is channel shaped and forms a housing for the friction wheel and 95 other parts in the vicinity thereof when this arm is in closed position. Depending ears 30 are provided on the side walls 31 of this arm and these are journaled on the shaft 17. Each of the side walls 31 of this arm is pro- 100

vided with an elongated slot as at 32 and the shaft 28 extends through these slots. Flanges as 33 may be provided along the longitudinal edges of the slots 32 to reinforce such edges and provide wider faces in contact with the shaft 28. Such flanges may be formed by striking up the metal of the side walls in the formation of the slots 32. The shaft 28 and the slots 32 form a pin and slot connection by means of which the snuffer arm is actuated by the member 13. The ability of the shaft 28 to revolve provides a roller action within the slots 32 which insures smooth and easy operation of the parts. A spring 34 acting against the snuffer arm normally retains the actuating member in raised position and causes the snuffer to press firmly on burner 6 in the manner described. An end web as 35 between the webs 9 and 10 may be provided and this will act as a shield for the burner.

The eccentric action produced by the spacing of the axes 11 and 17 provides a variable speed of rotation of the wheel 12, or in other words a snap action. The wheel rotates slowly as the cap is being raised clear of the wick, then rapidly to provide the shower of spark, and then more slowly as the finger piece approaches its lowest position. As no stop is present to limit the upward movement of the member 13, pressing contact of the snuffer and the burner is insured when the actuating member is released.

In the operation of the device the finger piece 25 is depressed from the normal position indicated in Fig. 1 to that shown in Fig. 2. The downward movement of the shaft 28 in this finger piece acting in the slots 32 causes the snuffer arm 18 to swing about the axis of the shaft 17 into its raised position or substantially that shown in Fig. 2. At the same time the ratchet arm 22 rotates the ratchet 16 one tooth distance or approximately 90° and carries with it the friction wheel 12, causing the teeth on the periphery of this wheel to act against the upper extremity of the pyrophoric metal 14. This projects a shower of sparks upon the wick 8 of the burner and lights the same. The parts will remain in this position and the lighter will continue to burn as long as the finger piece is held in its depressed position. As soon as the finger piece is released the spring 34 causes the snuffer arm to return to its normal or lowered position over the burner, extinguishing the flame thereon. This movement of the snuffer arm acts through the pin and slot connection to cause the actuating member to swing upwardly to its raised position. At the same time the ratchet arm 22 is advanced on the ratchet 16 to engagement with the next tooth. The friction wheel 12 remains stationary during this return movement of the parts. This completes the cycle of operations and the parts are now in position to repeat the same when desired.

It is obvious from the foregoing description that the lighter is simple and durable in construction and efficient and dependable in action. The long leverage provided by the member 13 greatly facilitates the operation of the device. The mounting of the snuffer arm on an axis further removed from the burner than the axis of the friction wheel makes it possible to swing the snuffer a considerable distance from the burner and thus not only prevents the snuffer from becoming tarnished by the flame but provides more available space about the burner which is advantageous particularly when a pipe is to be lighted. The pin and slot connection enables the snuffer to be readily lifted by the actuating member without the use of racks and pinions or other gearing which in such a relation are liable to cause trouble and are generally the first parts of the lighter to wear out. Furthermore this connection permits the replacement of the snuffer on the burner as soon as the finger piece is released. Firm pressure of the snuffer on the burner is always insured when the finger piece is not depressed.

It will thus be seen that there is provided a device in which the various objects of this invention are achieved and that the same is well adapted to meet the hardest conditions of practical use.

As many possible embodiments may be made of the above invention and as many changes might be made in the embodiment above set forth, it is to be understood all matter hereinbefore set forth or shown in the accompanying drawing is to be interpreted as illustrative and not in a limiting sense.

I claim:

1. In construction for lighters and the like, in combination, a fuel tank having an elongated top wall, a wick projecting from said wall adjacent one end thereof, a snuffer for said wick journaled on said top wall substantially mid-way between the ends thereof, an abrasive wheel journaled on said wall adjacent said wick, and a manually operable lever for actuating said wheel and said snuffer, said lever being fulcrumed at the axis of said wheel and extending over said tank substantially to the opposite end of said top wall from said wick.

2. In construction for lighters and the like, in combination, a fuel tank having an elongated top wall, a burner adjacent one end of said wall, a snuffer for said burner journaled on said wall substantially midway between the ends thereof, an abrasive wheel journaled on said wall intermediate said burner and the axis of said snuffer, a pyrophoric member co-operating with said wheel, and means for actuating said snuffer and said wheel including a pair of arms pivotally mounted on the axis of said wheel and extending therefrom substantially longitudinally of

said top wall toward the end opposite that having the burner thereon, one of said arms being disposed on each side of said snuffer, and a finger piece on the free outer end portions of said arms for manually actuating said arms.

3. In construction for lighters and the like, in combination, a fuel tank having an elongated top wall, a burner adjacent one end of said wall, a snuffer for said burner journaled on said wall substantially midway between the ends thereof, an abrasive wheel journaled on said wall intermediate said burner and the axis of said snuffer, a pyrophoric member co-operating with said wheel, and means for manually actuating said snuffer and said wheel including a pair of arms pivotally mounted on the axis of said wheel and extending therefrom substantially longitudinally of said top wall toward the end opposite that having the burner thereon, one of said arms being disposed on each side of said snuffer, a finger piece on the free outer ends of said arms, and a pin and slot connection between said arms and said snuffer whereby said snuffer is lifted when said finger piece is depressed.

4. In construction for lighters and the like, in combination, a fuel tank having an elongated top wall, a burner adjacent one end of said wall, a snuffer for said burner journaled on said wall substantially midway between the ends thereof, an abrasive wheel journaled on said wall intermediate said burner and the axis of said snuffer, a pyrophoric member cooperating with said wheel, and means for manually actuating said snuffer and said wheel including a pair of arms pivotally mounted on the axis of said wheel and extending therefrom longitudinally of said top wall toward the end opposite that having the burner thereon, one of said arms being disposed on each side of said snuffer, a finger piece on the free outer ends of the said arms, a pin and slot connection between said arms and said snuffer and a ratchet arm and ratchet connection between said snuffer and said wheel whereby said snuffer is lifted from said burner and said wheel rotated when said finger piece is depressed.

5. In construction for lighters and the like, in combination, a fuel tank having an elongated top wall, a wick projecting from said wall adjacent one end thereof, an abrasive wheel journaled above said wall, a pyrophoric element cooperating with said wheel, a snuffer for said wick journaled on said tank over said wall, an actuating lever for said wheel fulcrumed on the axis of the wheel, and means acting to multiply the movement of the wheel relative to the movement of the lever.

6. In construction for lighters and the like, in combination, a fuel tank having an elongated top wall, a wick projecting from said

wall adjacent one end thereof, an abrasive wheel journaled above said wall near said wick, a pyrophoric element cooperating with said wheel, a snuffer journaled on said tank on the opposite side of said wheel from said wick and connected to said wheel, an actuating lever for said wheel fulcrumed on the axis of the wheel, and means connecting said lever with said snuffer and acting to effect movement thereof in response to an actuation of said lever, said parts acting to give a greater angular movement to the wheel than is the angular movement of the lever.

7. In construction for lighters and the like, in combination, a fuel tank having an elongated top wall, a wick projecting from said wall adjacent one end thereof, an abrasive wheel journaled above said wall, a pyrophoric element cooperating with said wheel, a snuffer arm journaled on said tank on the opposite side of said wheel from said wick and extending over said wick, a snuffer on said arm, and an actuating lever for said snuffer and said wheel mounted to swing about an axis between said wick and the axis of said snuffer arm and extending toward the opposite end of said wall from said wick, said lever being shaped to straddle the axis of said snuffer when depressed.

8. In construction for lighters and the like, in combination, a fuel tank, a wick projecting from said tank, an abrasive wheel mounted on said tank, a pyrophoric element cooperating with said wheel, a pair of crossed levers the fulcrum point of each located nearer the free end of the other than is the fulcrum point of the other mounted for movement on said tank, one of said levers forming a finger piece and the other a snuffer arm, a snuffer for said wick on said arm, and means responsive to actuation of said finger piece whereby said snuffer is raised and said wheel is turned.

9. In construction for lighters and the like, in combination, a receptacle having an elongated upper wall for the mechanism, a wick projecting through said wall, a sparking wheel adjacent said wick, a snuffer mounted on a horizontal axis the other side of said wheel from said wick and adapted when depressed to cover said wick, a depressible finger piece adapted to be moved downward to actuate the lighter, a connection between said finger piece and said snuffer to raise said snuffer a substantial distance in response to depression of said finger piece, a ratchet wheel adapted when rotated to rotate said sparking wheel, pawl means pivoted to said snuffer at a point in the latter to partake of a proportionate amount of the said substantial movement given said snuffer in response to the said depression of said finger piece and thereby to give said pawl means a path of movement so close to said ratchet wheel as will maintain said pawl means in engagement

- with said ratchet wheel throughout the said proportionate movement of said pawl means by said snuffer, and spring means yieldingly urging said pawl means against said ratchet 5 wheel thereby to cause said pawl means, throughout its entire retrograde movement as said snuffer is returned to snuffing position, to ride over said ratchet wheel without rotating said ratchet wheel and sparking wheel.
10. In construction for lighters and the like, in combination, a receptacle for liquid fuel having an elongated top portion, a pyrophoric tube in said receptacle having therein a spring and a piece of pyrophoric material, a sparking wheel above said pyrophoric material mounted on a horizontal axis, a wick projecting above the top portion, a snuffer member pivoted on a horizontal axis on the other side of said wheel from said 15 wick and having a snuffer cap, a ratchet wheel directly connected to said sparking wheel, a pawl member pivoted to said snuffer member and engaging said ratchet wheel, a push finger piece having a broad operating portion entirely located above said top portion and behind the rear end of the snuffer member in all positions of the snuffer member, and a pin and sliding bearing connecting the snuffer member and the finger 20 piece adapted to move the snuffer cap a greater distance than the operating portion of the finger piece is moved, said pin being carried by said finger piece and having a path of movement, in response to operating 25 movement of said finger piece, that approaches the axis about which said snuffer member is pivoted.
11. In a construction for lighters and the like, in combination, a fuel tank, an abrasive 30 wheel mounted on said tank, a pyrophoric member cooperating with said wheel, a wick projecting from the top of said tank on one side of said wheel and extending into said tank, a snuffer mounted on said tank on the 35 opposite side of said wheel from said wick, a depressible finger piece pivoted on an axis intermediate said wick and the axis of said snuffer, means actuated by said finger piece and engaging said snuffer to cause said snuffer 40 to be lifted from said wick when one end of said finger piece is depressed, and means brought into action in response to depression of said finger piece for causing said wheel to be rotated simultaneously with the 45 raising of said snuffer whereby to ignite the wick.
12. In a construction for lighters and the like, in combination, a fuel tank having an elongated top wall, a wick projecting from 50 said wall adjacent one end thereof and extending into the fuel tank, an abrasive wheel journaled on said wall on an axis parallel to said wall and adjacent said wick, a pyrophoric member cooperating with said wheel, 55 a snuffer member journaled on said wall on the opposite side of said wheel from said wick, a manually operable actuating lever movable in a vertical plane and journaled between the axis of the snuffer and the wick and extending therefrom rearwardly between the planes of the sides of the fuel tank, a pin and slot connection between the lever and the snuffer, means operated by said manually operable actuating lever for rotating the wheel, and spring means to move the parts to the 60 normal position in which the snuffer covers the wick.
13. In construction for lighters and the like, in combination, a fuel tank, a wick projecting from the top of said tank and extending into the fuel in said tank, an abrasive wheel journaled on said tank adjacent said wick, pyrophoric means cooperating with said wheel, a snuffer member for said wick journaled upon a horizontal axis and extending over said wick, a manually depressible actuating member for said snuffer member and located above said fuel tank, one of said members being made of pressed metal 65 and having a slot therein, a flange along the longitudinal edge of said slot extending inwardly from one of the side walls of the member which is formed of pressed metal, a roller carried by the other of said members and adapted to roll along said slot and engage said flange, and spring means urging said depressible actuating member upwardly and said snuffer member downwardly into snuffing position.
14. In construction for lighters and the like, in combination, a fuel tank, a pair of crossed levers extending across the top of said tank, each lever having a top portion and depending side portions, the width of one lever being less than the width of the other so that the depending side portions thereof are received between the depending side portions of the other, means supported by said tank and passing through the depending side portions of said levers for fulcruming the latter on said tank, the fulcrum point of each lever being located nearer the free end of the other than is the fulcrum point of the other, one of said levers forming a finger piece and the other a snuffer arm, a wick projecting from said tank at a point underneath said snuffer arm lever and between the depending side portions thereof, an abrasive wheel mounted on said tank at a point on the latter that is underneath one of said levers and between the depending side portions thereof, a pyrophoric element cooperating with said wheel at that side of the latter toward said tank, a snuffer carried by said snuffer arm lever at a point thereon to cover said wick when said snuffer arm lever is in normal position, and means responsive to actuation of said finger piece lever whereby said snuffer arm lever is swung about its fulcrum to raise said snuffer from the wick and said wheel is turned.

15. In construction for lighters and the like, in combination, a fuel tank, a wick projecting from said tank, an abrasive wheel mounted on said tank, a pyrophoric element cooperating with said wheel, a pair of crossed levers the fulcrum point of each located nearer the free end of the other than is the fulcrum point of the other mounted for movement on said tank, one of said levers forming a finger piece and the other a snuffer arm, a snuffer for said wick on said arm, operating connections between said levers whereby said snuffer arm lever is swung to raise said snuffer from the wick in response to actuation of said finger piece lever, and connections between said snuffer arm lever and said abrasive wheel for rotating the latter when said snuffer arm lever is swung to remove the snuffer from said wick.
20. In construction for lighters and the like, in combination, a fuel tank, a wick projecting from said tank, a pair of crossed levers overlying and extending along said tank, each lever having a top portion and depending side portions, the width of one lever being less than the width of the other so that the depending side portions thereof are inter-fitted between depending side portions of the other, a pair of spaced shafts supported from said fuel tank, one for each lever and each passing through the depending portions of its lever for fulcrumming said lever with respect to said tank, said shafts being spaced so that the fulcrum point of each lever is located nearer the free end of the other than is the fulcrum point of the other, one of said levers forming a finger piece and the other a snuffer arm, the snuffer arm lever having a part normally overlying the point at which said wick projects from said tank, a snuffer carried by said part of said snuffer arm lever encompassing said wick, the depending side portions of said finger piece lever being cut away and the shaft of said snuffer arm lever being accommodated in the cut away parts of said side portions as said finger piece lever is swung about its shaft, an abrasive wheel mounted on said tank, a pyrophoric element cooperating with said wheel at a side thereof toward said tank, and connections whereby said snuffer arm lever is swung to raise said snuffer from the wick and said abrasive wheel is turned, said connections operating in response to movement of said finger piece lever.
25. In construction for lighters and the like, in combination, a fuel tank having an elongated top wall, a wick projecting upwardly from said tank adjacent one end of said wall, a pair of levers overlying and extending along said top wall and mounted for pivotal movement with respect thereto, each lever having a top portion and depending side portions, the top portions of said levers normally extending substantially parallel to said top wall, the top portion of one of said levers forming a finger piece, whereby the lever may be depressed, and the other of said levers forming a snuffer arm, a snuffer carried by said snuffer arm lever at the free end thereof, a wick projecting through said top wall at one end thereof and in position to be covered by said snuffer, an abrasive wheel mounted above said top wall intermediate the ends of the latter and between depending side portions of one of said levers and intermediate the free ends of said levers, the axis of said wheel being spaced from the pivot of said snuffer arm lever, a pyrophoric element projecting upwardly through said top wall into contact with said wheel, said snuffer arm lever having a greater angular movement than said finger piece lever, and operating connections between said finger piece lever, said snuffer arm lever, and said abrasive wheel whereby, in response to depression of said finger piece lever by manual movement of its top portion toward said top wall, said snuffer arm lever is swung upwardly through said greater angular movement to uncover the wick and said abrasive wheel is rotated against said pyrophoric element.
30. In construction for lighters and the like, in combination, a fuel tank, a pair of crossed levers extending across the top of said tank and fulcrumed on said tank, each lever having a top portion and depending side portions, the depending side portions of one lever being received between the depending side portions of the other, the fulcrum point of each lever being located nearer the free end of the other than is the fulcrum point of the other, one of said levers form-
35. ing a finger piece and the other a snuffer arm, a wick projecting from said tank underneath said snuffer arm lever, an abrasive wheel mounted on said tank underneath one of said levers and between the depending side portions thereof, a pyrophoric element cooperating with said wheel at that side of the latter toward said tank, a snuffer carried by said snuffer arm lever to cover said wick when said snuffer arm lever is in normal position, said snuffer arm lever having a range of movement about its fulcrum sufficient to carry it from said normal position to a position in which said snuffer uncovers said wick, an operating connection between said snuffer arm lever and said wheel whereby the latter is turned as said snuffer arm lever is moved to uncover the wick, and means responsive to actuation of said finger piece lever for controlling movement of said snuffer arm lever from one of said positions to the other.
40. In construction for lighters and the like, in combination, a fuel tank having an elongated top wall, a wick projecting upwardly from said tank adjacent one end of said wall, a pair of levers overlying and extending along said top wall and mounted for pivotal movement with respect thereto, each lever having a top portion and depending side portions, the top portions of said levers normally extending substantially parallel to said top wall, the top portion of one of said levers forming a finger piece, whereby the lever may be depressed, and the other of said levers forming a snuffer arm, a snuffer carried by said snuffer arm lever at the free end thereof, a wick projecting through said top wall at one end thereof and in position to be covered by said snuffer, an abrasive wheel mounted above said top wall intermediate the ends of the latter and between depending side portions of one of said levers and intermediate the free ends of said levers, the axis of said wheel being spaced from the pivot of said snuffer arm lever, a pyrophoric element projecting upwardly through said top wall into contact with said wheel, said snuffer arm lever having a greater angular movement than said finger piece lever, and operating connections between said finger piece lever, said snuffer arm lever, and said abrasive wheel whereby, in response to depression of said finger piece lever by manual movement of its top portion toward said top wall, said snuffer arm lever is swung upwardly through said greater angular movement to uncover the wick and said abrasive wheel is rotated against said pyrophoric element.
45. In testimony whereof, I have signed my name to this specification this 11th day of December, 1928.
50. ROBERT S. BLAIR.
